UNITED STATES PATENT OFFICE.

ALLEN D. CARDWELL, OF NEW YORK, N. Y.

TELEGRAPH TYPE-WRITER.

1,070,407.

Specification of Letters Patent. Patented Aug. 19, 1913.

Application filed December 22, 1910. Serial No. 598,755.

To all whom it may concern:

Be it known that I, ALLEN D. CARDWELL, a citizen of the United States, and a resident of the city of New York, borough of Brooklyn, county of Kings, State of New York, have invented certain new and useful Improvements in Telegraph Type-Writers, of which the following is a specification.

The invention will be understood by reference to the accompanying drawings, in which—

Figure 1 is a plan view; Fig. 2 a side elevation with some of the parts broken away; Fig. 3 a transverse view on the plane of the line 3—3 of Fig. 1 looking in the direction of the arrow; Fig. 4 a plan view of certain parts of Fig. 1 on an enlarged scale showing a different position of the parts; Fig. 5 a view similar to Fig. 4 showing another position of the parts; Fig. 6 a longitudinal section on the plane of the line 6—6 of Fig. 1 looking in the direction of the arrows; Fig. 7 a development of the type wheel for the purpose of explaining the invention; and Fig. 8 a diagrammatic view of the circuits.

Similar reference numerals indicate similar parts in the several views.

Referring to the drawings, the numeral 1 designates a type wheel which, in the form shown, is divided into four equal sections, each section having sixteen letters, numerals, or other symbols thereon. In an apparatus constructed by me I have used forty-eight characters, but provision is made in the machine illustrated herein for sixty-four characters. In Fig. 6 the characters are shown on the upper one of the four sections of the wheel. In a vertical direction the characters do not take up the entire height of a section, and the space which is hereafter referred to as being between the rows of type characters is the plain surface of the wheel between the horizontal rows. The type wheel 1 is splined on a vertical shaft 2, the latter being supported in suitable bearings in the frame of the machine, and is adapted to be rotated by a pinion 3 keyed thereon, and a toothed sector 4 on the end of an oscillating arm 5. The printing hammer 6 has a direct forward movement only and the type wheel is so disposed that normally the type hammer is opposite the space between the second and

third rows of the wheel. This, therefore, necessitates not only a rotary movement of the wheel, but also a vertical movement in order to bring the proper section into printing position. The rotary movements necessary to be imparted to the type wheel may best be explained by reference to Fig. 7. I have here for convenience developed the type wheel showing spaces for sixty-four characters, sixteen letters of the alphabet being in the top row. The normal position of the hammer is indicated by the black square. The positioning of the type wheel is effected by three groups of magnets, the first and second groups effecting a rotation of the wheel, and the third group effecting a longitudinal movement of the wheel to bring the row on which the selected character is in printing position. The first group comprises the magnets A, B and C, and the second group magnets D, E and F. If now in Fig. 7 we assume the line $x-x$ to be the central or starting line, that is, the vertical plane passing through the axis of the hammer 6, the purpose is to rotate the wheel from this starting or normal position to its proper horizontal position for any of the sixteen characters on any one of the four rows in two movements. It will be noted that the starting line $x-x$ is intermediate two characters. The first movement of the wheel, if to the left, on the diagram, will move the wheel so that the lines a' , or a^2 , will be in the vertical plane of the printing hammer; or, if to the right, a^3 or a^4 will be in said plane. The second movement is designed to carry the wheel to its ultimate horizontal position, and as the first movement positions the wheel relatively to the hammer intermediate two characters, the second movement must move the wheel either to the right or to the left one-half space or one and one-half spaces to position the selected character in the vertical plane of the axis of the hammer. This may be explained by assuming that the letter n is to be printed. The first movement will rotate the wheel to such position that the space between the letters n and o , designated by the arrow a^2 , will be brought to coincide with the vertical plane of the axis of the printing hammer, designated by the line $x-x$. The second movement will

move the type wheel one-half space to the right to bring the letter *n* into said plane. From this description the movements either to the right or left of the normal position 5 *w—x* for any letter or character may be readily traced, and it will be seen that the second movement of the wheel may be either in the same or in the reverse direction of the first movement. Having positioned the 10 wheel horizontally, the third group of magnets *G, H* and *I* is utilized to move the wheel longitudinally of its axis to bring the row containing the selected character to be printed in proper relation to the hammer. 15 For example, if the selected character is in the first row, the wheel will be moved down one and one-half spaces. If in the third row, one-half space up. The division of the type wheel as described is more convenient 20 than having all the characters in a single row.

In the particular embodiment of the invention here illustrated, each section of the type wheel 1 has sixteen letters, numerals, 25 or other characters thereon, and the pinion 3 has a corresponding number of teeth. Secured to the side of the pinion 3 is a star wheel 7 also having sixteen teeth so set that the points of the teeth are in vertical alinement with the spaces between the characters on the wheel. Opposite the star wheel is a pawl 8 on the end of an arm 9 fast to the armature of printing magnet *J*, the normal position of said pawl being out of engagement 30 with the star wheel, as shown in Fig. 4. When the printing magnet *J* is energized, on the breaking of the final impulse, the pawl 8 is thrown into engagement with the star wheel to hold the type wheel rigid 35 and to bring it into exact printing position, if it should be slightly out of alinement. When magnet *J* is deenergized, the pawl 8 is thrown out of engagement with the star wheel 7 by spring 10. When the machine is 40 operated at high speeds the type wheel is liable to oscillate slightly and for that reason I provide the star wheel and pawl as just described in order to hold the type wheel rigid.

50 Before giving a detail description of the mechanism and of its mode of operation, I will state that the positioning magnets comprised in the three groups above referred to are selectively energized by impulses from 55 a sending station, these impulses being of different characteristics, as a long or short positive, or a long or short negative, or a strong or weak positive, or a strong or weak negative, as is well known in printing systems. For example, the magnets *A, D* and *G* may each be operated by a short positive impulse; the magnets *B, E* and *H* by a short negative impulse; magnet *C* by a long positive or negative impulse in conjunction with 60 the magnets *A* or *B*; magnet *F* by a long

positive or negative impulse in conjunction with the magnet *D* or *E*; and the magnet *I* by a long positive or negative impulse in conjunction with the magnet *G* or *H*. The magnet *A* alone or *B* alone, or either one in 70 conjunction with magnet *C*, is energized by the first impulse. In the second group either the magnet *D* or *E* alone, or either one in conjunction with magnet *F*, is energized by the second impulse. In the third 75 group the magnet *G* alone or *H* alone, or either in conjunction with the magnet *I*, is energized by the third impulse, these magnets moving the type wheel to its ultimate or printing position. These magnets are not 80 energized directly by the line currents or line relays but by intermediate relays shown in Fig. 8, as will be described hereafter. With this general explanation I will now proceed to describe the machine in detail, 85 taking first the group of magnets *A, B* and *C* and the parts actuated thereby.

The first group of magnets.—As above stated, and by referring to the diagram in Fig. 7, the magnet *A* is designed to rotate 90 the type wheel two type spaces to the right, and in conjunction with magnet *C* six spaces to the right. The magnet *B* alone when energized is designed to move the type wheel two type spaces to the left and, when energized in conjunction with magnet *C*, six 95 type spaces to the left. The means for effecting these movements are as follows: Between the two magnets *A* and *B* is an armature 11 pivoted on a shaft 12 having a 100 bearing in the base 13 and a standard 13'. In order to transmit the movement of armature 11 to the sector arm 5, I connect to the armature 11 a plate 14 by means of a shoulder screw 15, said screw passing 105 through an elongated slot 16 of said plate and bearing against the walls of said slot. The armature 11 and the plate 14 and a plate 17 above the plate 14 are extended beyond the shaft 12 and are secured by a 110 shoulder screw 18, suitable washers being interposed between the armature and the plates, as shown in Fig. 6. The plate 14 has a second longitudinal slot 19, as shown in Fig. 6, through which the screw 18 passes. 115 In order to prevent any lost motion sideways of the plate 14, the screws 15 and 18 bear against the side walls of the slot 16 and 19, respectively. In the plate 14 there is also a diagonal or cam slot 20 in which 120 is a roller on the end of stud screw 21, which stud is secured to plate 17, the roller on the lower end of the stud bearing against the side walls of the cam slot 20. Near the outer end of the plate 17 is a post or pin 22 125 which projects upwardly between and bears against two fingers 23, said fingers being supported on shaft 12 between suitable collars, as shown in Fig. 6, and are held together on said shaft by a spring 25 secured 130

to the outwardly bowed heads of the fingers 23, as shown in Fig. 5. Secured to and depending below the sector arm 5 is a screw stud 24 which is also between and bears against the fingers 23. Set into the under side of the armature 11 is a stud screw 26 which projects downwardly and between and bears against two fingers 27 similar to the fingers 23. At one end the said fingers are supported on the shaft 12 between suitable collars, as shown in Fig. 6, and are spring pressed together by a spring 28 similar to the spring 25 for holding together the fingers 23. At their outer ends the fingers 27 bear against the sides of a stop stud 29 set into the base 13.

The function of the studs 26 and 29 and spring fingers 27 is to hold the armature 11 in its normal position and also to return it to normal position after it has been moved to one side or the other. The function of studs 24 and 22, and spring 25, and fingers 23 is to hold the sector arm 5 in a definite relation with plate 17 but to allow the sector arm 5 to overthrow, without danger to the parts under abnormal conditions. The function of plate 14 and its diagonal slot 20 is to vary the relation of the sector arm 5 with respect to the armature 11 when the magnets D, E and F are energized. When the magnet A or B is energized the movement of armature 11 carries with it the plate 14 by means of studs 15 and 18. The movement of plate 14 is transmitted to plate 17 through stud 21 and diagonal slot 20 and the movement of plate 17 is transmitted through stud 22 to spring-pressed fingers 23, and the movement of the latter through stud 24 is transmitted to sector arm 5. The movement of these parts is arrested by the forward end of armature 11 contacting with one of the rectangular heads 34 or with the standard 30, as will be presently described. When operating at high speeds, when the movement of armature 11 is arrested, the parts intermediate the armature and the sector arm 5 permit an overthrow of the latter, but it is immediately restored to its proper position by the action of the spring fingers 23.

Secured to the base 13 at the forward end of armature 11 are two standards 30 which support a plate 31. Extending through openings in the base 13 are two pins 32, one on each side of the center of the plate 31. Integral with these pins are collars 33, and above the collars the pins are formed with rectangular heads 34 which project upwardly through openings in the plate 31 and serve, when projected upwardly, as stops to limit the stroke of armature 11, and which, when withdrawn, will permit further movement of the armature, as explained later. The pins 32 and their rectangular heads 34

65 are normally pressed upwardly to hold the heads 34 in their projected positions, by springs 35 bearing against collars 33 and the base 13.

The magnet C is mounted below the base 13 and its armature 36 is made in the form 70 of a bell crank with its forward end widened and provided with openings through which the pins 32 pass, said pins having check nuts 37 thereon. It will be readily understood from this that when magnet C 75 is energized the outer end of its armature will be depressed to thereby pull down upon the pins 32, the extent of movement of armature 36 being sufficient to draw the heads 34 of said pins flush with the plate 31. A 80 stop screw 38 limits the upward movement of the armature 36 and thereby the upward movement of the pins 32.

The operation of the mechanism so far described is as follows: In their normal positions the armature 11 is held centrally between magnets A and B, and centrally between the stops 34 by the spring pressed arms 27 and studs 26 and 29. So long as the magnet C is deenergized the stops 34 will 85 remain in their upward or normal position to thereby limit the movement of armature 11 either to the right or left the equivalent of two type spaces on the type wheel, or two teeth on the pinion 3 and star wheel 7; that is, by referring to the diagram of Fig. 7, to either of the positions a' or a'' . When magnet C is energized the stops 34 will be retracted permitting thereby the movement of armature 11 a distance equivalent to six type 90 spaces, or six teeth of the pinion 3 and star wheel 7, or, by referring to the diagram of Fig. 7, to either of the positions a^2 or a^4 . Either one of these four positions is determined by the first impulse; that is, the first 95 impulse may energize the magnet A alone or B alone, or A and C in combination, or B and C in combination, giving one of the four positions a' , a'' , a^2 or a^4 of Fig. 7. Assuming that the magnet A alone is energized, then as armature 11 is attracted, its forward end will contact with the upper stop 34, as viewed in Fig. 1. To prevent the sector arm 5 being subjected to the shock and jar of the sudden stopping of armature 11 100 105 110 by the stop 34, I have provided the mechanism above described intermediate the armature and sector arm; that is, when armature 11 is brought to rest, the inertia of sector 5 tends to keep it moving in the direction of its initial movement; that is, forward. It is, however, brought to rest and to a central position relatively to armature 11 by means of stud 24, spring pressed fingers 23, stud 22, plate 17, stud 21, plate 14 and screws 115 120 125 130 135 from stud 22. The other parts; that is, plates 14 and 17, come to rest with armature 11. When the inertia of sector arm 5 has been overcome by tension of the spring 25, it will have moved the type wheel the distance of two type spaces. If armature B alone is energized, the movement of the parts above described will be in the reverse direction.

- 10 If the first impulse is to carry the type wheel to either of the positions a^2 or a^4 , then magnet C is energized to withdraw the stops 34, thereby permitting a movement of armature 11 and sector arm 5 with corresponding 15 rotation of the type wheel to either of the positions a^2 or a^4 , it being understood that when the stops 34 are withdrawn either magnet A is energized in conjunction with C, or magnet B with C. When the stops 34 20 are withdrawn, the armature 11 will rest against standards 30. When any magnet of the first, second or third group is energized, it remains energized to hold the wheel in the position to which it is brought by that 25 particular magnet until the character has been printed.

Second group of magnets, D, E and F.—As before stated, it is necessary to give the type wheel two rotary movements in order 30 to position the selected character in the vertical plane of the axis of the hammer. The second rotary movement is effected by the group of magnets D, E and F, which are designed to give an additional movement of 35 the sector arm 5 to move the type wheel one-half space or one and one-half spaces to the right or left of the positions a' , a^3 , a^2 , or a^4 to which the wheel was brought by the first impulse. To this end the armature 39 40 is pivoted on a shaft 40 held in suitable bearings in the base and in a standard supported on the base. Set into the under side of the armature is a stud 41 (see Fig. 1) which projects downwardly between two 45 spring-pressed fingers 42, these fingers at their rear ends bearing against the shaft 40 between suitable collars and pressed toward each other by a spring 43. Projecting upwardly from the base between said fingers 50 in proximity to the stud 41 is a second stud 44, this construction being substantially similar to the fingers 27 and studs 26 and 29 used in connection with armature 11.

Armature 39 is extended forward so as 55 to pass over a plate 45 supported upon standards and similar to the plate 31, and at its outer end carries a pivotal stud on which is mounted one end of a link 46, the other end of said link being connected to a 60 pivot stud carried by arm 47 secured to plate 14. The plate 45 is formed with openings through which project stops 48 carried on spring pressed pins 49 in all respects similar to the stops 34 and pins 32, heretofore described.

The second rotary movement of the type wheel is effected when magnet D alone is energized or magnet E alone, or magnet D in conjunction with F, or magnet E in conjunction with F. So long as magnet F is deenergized, the stops 48 remain in their upward position thereby limiting the movement of armature 39 to that which is effected by magnet D alone or E alone. In Fig. 4 I have shown the parts in the position assumed after the first impulse and with the armature 39 in its normal position. If now magnet D alone is energized the armature 39 will, when attracted, be brought to rest against the right-hand stop 48. This movement of armature 39 is communicated through link 46 to plate 14 moving the latter longitudinally forward, this movement being permitted by reason of the slots 16 and 19 in said plate. As the plate 14 moves forward the walls of the diagonal or cam slot 20 bear against the stud 21 and, as said stud is fast to plate 17, the latter will be displaced angularly relatively to plate 14. As shown in Fig. 5, the plate 17 is formed in its forward end with a transverse slot 17' which permits of this angular movement of said plate about the shoulder screw 18 as a center. This angular movement of plate 14 is communicated through stud 22, spring 23 and stud 24 to sector arm 5, the length of armature 39 and the angle of slot 20 being so proportioned that the ultimate movement of sector arm 5, when magnet D alone or E alone is energized, will 100 move the type wheel one-half of a type space to the right or left. If magnet F is energized in conjunction with magnet D or magnet E, then the stops 48 will be withdrawn to permit of an additional movement of 105 armature 39 and of sector arm 5 in the same direction, the additional movement permitted by withdrawing stops 48 being equivalent to one full type space so that when magnet F is energized the type wheel 110 will be moved one and one-half spaces to the right or left.

When magnet E alone is energized then a rearward movement is imparted to plate 14 to thereby rotate the type wheel one-half space in a direction reverse to that imparted by magnet D. When magnet F is energized in conjunction with E a further rearward movement will be imparted to plate 14, corresponding with the forward 120 movement when magnets D and F are both energized.

The third group of magnets, G, H, I.—Having now rotated the wheel so that the selected character is in proper horizontal position relatively to the hammer, it is necessary that a longitudinal movement be given the type wheel to properly position the selected character with respect to the hammer 6. This final movement of the type 130

wheel is effected by the third group of magnets G, H and I, shown in Figs. 1, 2 and 3. Between magnets G and H is an armature 50 pivoted on a shaft 51, said armature being held in its normal position by fingers 52 which, at their rear ends, embrace the shaft 51 and are held pressed toward each other by a spring 53. Secured to the base 13² is a stud 54 which projects between the 10 spring pressed fingers 52, and secured to the under side of said armature 50 is a stud 55 which also projects between said fingers, these studs being shown in dotted lines in Fig. 3. The fingers 52 and studs 54 and 55 15 are similar in all respects to the fingers 27 and studs 29 and 26, heretofore described in connection with Fig. 6. The armature 50 is extended forward over a plate 56 supported in standards and similar to the plate 20 31, and carries at its outward extremity a roller 57 (see Fig. 6) which enters a groove in the type wheel between the lower row and a collar 58. The plate 56 is provided with openings through which project stops 59 25 mounted on pins 60 spring pressed so as to hold the stops 59 above the surface of the plate 56. The pins 60 are connected to the T end of the bell crank armature 61 of magnet I. The stops 59 are similar in construction 30 to the stops 34, heretofore described.

As shown in Fig. 6, the type hammer 6 is opposite the center of the type wheel or intermediate the second and third rows of the wheel. When magnet G alone is energized, the outer end of arm 50 will be elevated so as to cause the roller 57 to bear against the under side of the wheel and thereby raise it so that the third row will be in alinement with the printing hammer 6. When magnet 35 H alone is energized, the outer end of armature 50 will be depressed, causing the roller 57 to bear against collar 58 and thereby depress the type wheel to bring the second row into alinement with the printing hammer. When magnets G and I are energized, the type wheel will be raised the space of one and one-half rows so as to bring the 40 fourth section of the wheel into proper alinement with the printing hammer. When magnets H and I are energized, the type wheel will be lowered the distance of one and one-half rows so as to bring the first section of the wheel into proper alinement with the hammer.

From the foregoing description it will be seen that the first group of magnets rotate the type wheel either two or six type spaces to the right or left of the normal position of the wheel relatively to the vertical plane 45 of the hammer, and that the second group of magnets move the type wheel one-half space or one and one-half spaces to the right or left of the position to which it was moved by the first group of magnets; that is, the 50 ultimate horizontal position of the type

wheel relatively to the hammer is either the sum of the two movements or the difference between the two movements. As, for example, by referring to Fig. 7, if the letter "i" is the selected character, the type wheel 70 will be moved the difference between the movement of two spaces to the left and one and one-half spaces to the right, equal to one-half space to the left. If the letter "l" 75 is the selected character, the ultimate horizontal position of the type wheel will be the sum of two spaces and one and one-half spaces to the left. The third group of magnets determines the longitudinal position of the type wheel, as already explained. 80

As explained later in connection with the diagram of Fig. 8, the impulses may come in such rapid succession that all of the impulses are received before the above-described mechanism has time to complete its 85 operation; that is, speaking only of the mechanical movements, the armature 39 of the second group of magnets may be operated before the armature 11 of the first group has completed its movement, or vice versa. In 90 the same manner the armature 50 of the third group of magnets may be operated before the armature of the first or second groups, or this movement may take place 95 intermediate the movements of the armature 95 of the first and second groups. In other words, the ultimate position of the type wheel is the resultant of the movements of armatures 11, 39 and 50 acting either simultaneously or in any one of the six sequences 100 represented by the combinations of the first, second and third groups in their relation to one another.

When operated at high speeds, there is apt to be a slight overthrow of the type 105 wheel and to secure the exact alinement of the selected character, I provide the star wheel 7 and pawl 8, as heretofore described.

The printing hammer 6 is mounted on a lever 62 pivoted on a shaft 63, and is held 110 in its outward or normal position by a spring 64 against a stop 65 fixed to the shaft 63. The shaft 63 is a part of or integral with the armature 66 of magnet J, said shaft having suitable bearings in the base and in 115 a standard mounted thereon. Armature 66, when actuated on the breaking of the final impulse, moves the pawl 8 into engagement with the star wheel and throws the printing hammer forward by means of the stop arm 120 65. After delivering its blow, armature 66 is retracted by spring 10.

The armature 66 is extended rearwardly, as shown in Fig. 1, and carries an insulated pin 67 bearing against two normally closed 125 contacts 68 in the main battery circuit. When magnet J is energized, these contacts 68 are opened so as to restore all magnets to normal. The opening of contacts 68, however, is so timed relatively to the printing 130

operation that the printing will have been accomplished before the contacts 68 are opened.

The particular form of apparatus shown 5 is that of a tape printing mechanism, the tape being fed from a reel 69 through a suitable guide 70, past an opening 71 therein (see Fig. 3), and then in contact with spring fingers 73 which press it against a 10 feed wheel 72. The latter is mounted on a shaft 78 and fed by ratchet wheel 74 actuated on the back stroke of armature 66 through the medium of a pawl 75 for both letter and word spacing. For the latter the 15 section of type wheel which is brought in front of the hammer is blank so that no impression is made on the paper.

The ribbon is wound on spools 76 and is fed on each printing operation by a worm 77 20 on the lower end of shaft 78 (see Fig. 2). The worm drives a gear wheel 79 on the shaft of the ribbon spools 76.

Having described the mechanical features 25 of the printing mechanism, I will now, by reference to the diagrammatic view in Fig. 8, describe the circuits of the working magnets. Instead of operating the magnets directly from the line currents I employ local 30 relays which are actuated by the main line relay or relays, one being shown at L. An advantage in using intermediate relays is that they can be adjusted to the character of the line impulses and will respond more rapidly thereto. Additionally, they serve 35 the purpose, when closed, of maintaining themselves closed and also maintaining current through the working magnets which they control.

As shown in Fig. 8, each magnet of the three 40 groups above described is controlled by a contact on a relay designated by the corresponding letter primed, the circuits for said relay being controlled by differentially wound local relays M and N, and contacts 80 and 45 81 on the main line relay. Relays M and N are so designed that when both windings are energized there will be no resultant magnetism. Similarly the printing magnet J is controlled by local relay J', which is also 50 differentially wound. The tongue of the main line relay L is normally held in central position relative to contacts 80 and 81 and is connected to one pole of the local battery at point 82, the other pole of said battery 55 being represented as connected to ground. The relays of the three groups of magnets are double wound, one winding to attract the armature and close its contact, and the other tending to maintain the said contact closed. 60 In this particular case the right-hand winding is that which primarily operates the relay, and the left-hand winding is used for holding purposes. The relays M, N and J' are primarily energized by the winding on 65 the right-hand side and are then neutralized

by the winding on the left-hand side when the holding current is supplied to the relays controlling the working magnets of the first, second and third groups. They are afterward energized and the armature actuated 70 by the winding on the left-hand side when the current in the winding on the right-hand side has been broken by the opening of the line relay contacts.

The relay L is a polarized relay and is 75 energized by impulses coming in from a distant station over the line, and the tongue of said relay is moved to the right or the left according to the polarity of the current. The impulse may be of long or short dura- 80

In order to actuate the working magnets to position the type wheel for the various characters thereon I have used the following combinations: + representing a short positive; ++ a long positive; - representing a short negative; -- representing a long negative. 85

To explain the action of the relays I will describe the operation thereof and of the 90 working magnets, assuming that the numeral 2 is to be printed and that a positive impulse will close contact 80, and a negative impulse will close contact 81. To print the numeral 2 requires a short positive, a long 95 negative, and a short positive impulse. The first or short positive impulse will close contact 80 and current will then flow from local battery from point 82, tongue of relay L, contact 80, armature 83 of relay N, armature 84 of relay M, right-hand winding of relay A', point 85, right-hand winding of relay C', right-hand winding of relay M, to ground. When relay A' is thus energized it closes contact 86; thus supplying current 100 from point 82 through the normally closed contacts 68, left-hand winding of relay M, thus neutralizing said relay, left-hand winding of relay A', contact 86, armature of relay A', working magnet A, to ground. When 105 working magnet A is thus energized, the type wheel will be rotated two spaces clockwise. Although current is flowing through right-hand winding of relay C', the armature of the latter is not moved for the reason that said relay is so designed as to operate only on a long impulse. When contact 80 is opened current is cut off from the first 110 circuit above described and the right-hand winding of relay M is deenergized. Current, however, continues through the second 115 above-described circuit closed by contact 86 and the left-hand winding of relay M being energized, closes both armatures 84 and 84' on contacts 87 and 87', respectively, to shift the circuits of contacts 80 and 81 to the second group of relays D', E' and F' and the corresponding working magnets. 120

The second impulse of the selected character being a long negative, contact 81 will 125

be closed, thus closing the circuit through armature 83'; armature 84' of relay M, contact 87' to right-hand winding of relay E', to point 91, right-hand winding of relay F', to right-hand winding of relay N, to ground. When E' is energized, contact 92 will be closed, thus permitting current to flow from point 82, closed contacts 68 to point 93, left-hand winding relay N, thus neutralizing said relay, point 94, left-hand winding E', contact 92, armature of E', working magnet E, to ground. When magnet E is energized, the type wheel will be rotated anti-clockwise. As this is a long impulse, relay F' will be energized to close its contact 95, thus energizing working magnet F and moving down the stops 48 to effect a movement of the type wheel one and one-half spaces in an anti-clockwise direction thus bringing the selected character in the plane x-x. When contact 81 is opened, the circuit including the right-hand winding of relay N is broken thus permitting the left-hand winding to attract armatures 83 and 83' to shift the circuits of contacts 80 and 81 to the third group of relays G', H' and I' of the corresponding working magnets. Having brought the selected character to its ultimate horizontal position, it remains to raise or lower the type wheel. This is effected by the third group of magnets, and for the numeral 2 the magnet G must be energized. The third impulse being a short positive, contact 80 and the following circuit will be closed:—point 82, contact 80, armature 83, contact 89 which was closed on the breaking of the previous impulse, right-hand winding of relay G', right-hand winding of relay I', right-hand winding of relay J', to ground. When G' is energized, contact 96 is closed and current flows from battery through contacts 68, point 97, left-hand winding of J', left-hand winding of G', contact 96, armature of G', working magnet G, to ground. When G is energized, the type wheel will be shifted one-half space upward to properly position it for the selected character. Since the last impulse was a short one, relay I' was not operated. When contact 81 is opened, relay J' is operated by the left-hand winding thereby closing contact 98 so that current will flow from battery through armature of J', contact 98, printing magnet J, to ground. When the printing magnet is thus energized, the hammer 6 will be moved to effect the printing. At the end of the printing blow contact 68 will be opened, thus opening all the holding circuits of the local relays and working magnets previously energized. When relay J' is opened, the printing magnet J will be deenergized, permitting contact 68 to close and the machine to return to normal position.

In the following table I give forty characters, the impulses in their order, and the

magnets energized to properly position the type wheel for printing:—

Character.	Impulses.			Magnets operated. 70
	1	2	3	
a.....	—	—	—	BC EF HI

From the foregoing table the circuits for any letter of the alphabet may be readily traced, it being remembered that the relays of magnets A, D and G are energized by positive line impulse irrespective of duration of the impulse; that the relays of magnets B, E and H are energized by a negative line impulse irrespective of the duration of the impulse; and that the relays of magnets C, F and I are energized by either a positive or a negative line impulse of definite duration. Also that relays M, N and J' are differentially wound, and that they are operated only when the contact of one of the relays of the corresponding group is closed and the main line relay contact 80 or 81 is opened.

In Fig. 8 I have shown the relays G' and H' shunted with suitable condensers 99 and 99', respectively, and relay I' shunted with a non-conductive resistance 100, so that the former are more readily responsive to short impulses and the last-named only to long impulses. The relays of the first and second groups may be provided with similar condensers and resistances.

From the foregoing table showing the magnets operated for printing the letters of the alphabet, any one skilled in the art can readily arrange a suitable system of impulses necessary for operating the magnets for numerals, punctuation marks, and other

100

130

characters on the type wheel and for word spacing. Although I have specified sixty-four characters on the type wheel, it is evident that a less number may be employed.

5. What I claim and desire to secure by Letters Patent of the United States is:—

1. A telegraph typewriter comprising a plurality of groups of working magnets, means for selectively energizing a magnet or 10 magnets of each group, a line relay and contacts therefor, and means for shifting the circuits of the line relay contacts to said groups successively.

2. A telegraph typewriter comprising a 15 plurality of groups of working magnets, groups of relays corresponding to said magnets and adapted to close the magnet circuits, a line relay and contacts therefor, circuits including the line relay contacts and 20 said relays, and means for shifting the circuits of said contacts to said groups of relays successively.

3. A telegraph typewriter comprising a 25 plurality of groups of working magnets, corresponding groups of relays, a line relay and contacts therefor, circuits including said contacts and relays, and a magnet for each group of circuits adapted when energized to shift the circuits of the line relay contacts to 30 the next succeeding group.

4. A telegraph typewriter comprising a 35 plurality of groups of working magnets, corresponding groups of relays adapted when energized to remain energized to close and maintain closed the corresponding working magnet, a line relay and contacts therefor, circuits connecting said contacts and said relays, and a magnet in each of said circuits adapted when energized to shift the circuits 40 of the line relay contacts from one group of relays to the next succeeding group.

5. A telegraph typewriter comprising a 45 plurality of groups of working magnets, groups of relays corresponding thereto, means for selectively energizing some of the relays of each group by currents of different polarity irrespective of duration and another relay of each group by a current of definite duration irrespective of polarity.

50. 6. A telegraph typewriter comprising printing mechanism including a type wheel, a plurality of groups of working magnets adapted when energized to move the type wheel, a relay for each of said magnets, 55 means for selectively energizing given relays for the selected characters to be printed by successive impulses thereby energizing the corresponding working magnet, means to effect the printing on the breaking of the 60 final impulse, and means for restoring the relays and working magnets to normal after the printing has been effected.

7. A telegraph typewriter comprising 65 printing mechanism including a type wheel, working magnets adapted when energized

to move said wheel, a relay for each of said magnets, a line relay and contacts therefor, circuits including said contacts and relays, means for shifting the line contact circuits by successive impulses, means to effect the 70 printing on the breaking of the final impulse and for restoring the working magnets and their corresponding relays to normal after the printing has been effected.

8. A telegraph typewriter comprising 75 three groups of three working magnets each, a relay for each of said magnets adapted when energized to close its circuit, two of the relays of each group adapted to be energized by currents of different polarity irrespective of duration, and the third relay of each group adapted to be energized by a current of definite duration irrespective of polarity.

9. In a telegraph typewriter the combination of a type wheel, mechanism for rotating said wheel comprising a plurality of groups of magnets, armatures for said magnets, and means intermediate said armatures and type wheel to effect the ultimate printing position 90 of said wheel for any given character thereon irrespective of the succession of movements of said armatures.

10. In a telegraph typewriter the combination of a type wheel, mechanism for rotating said wheel comprising a plurality of groups of magnets, armatures for said magnets, means for imparting movements of variable extent to said armatures, and means intermediate said armatures and type wheel 100 to effect the ultimate printing position of said wheel for any given character thereon irrespective of the succession of movements of said armatures.

11. A telegraph typewriter comprising a 105 plurality of groups of working magnets, corresponding groups of relays adapted to close the circuits of said magnets, a line relay and contacts therefor, circuits including said contacts and relays, and means for shifting the circuits of the line relay contacts to successive groups of relays irrespective of the length of duration of the line impulses.

12. A telegraph typewriter comprising a 110 plurality of groups of working magnets, corresponding groups of relays adapted to close the circuits of said magnets, a line relay and contacts therefor, circuits including said contacts and relays, said last-named circuits including a double wound relay 120 adapted to be energized on the opening of one of its windings to thereby shift the circuits of the line contacts to the next succeeding group of working-magnet relays.

13. In a telegraph typewriter the combination of a curved type-bearing surface, electromagnets, an armature adapted to be moved in opposite directions by said magnets, and mechanism actuated by said armature to move said type bearing surface in 125

opposite directions, and means to additionally move said mechanism from the position to which it is moved by said magnets.

14. In a telegraph typewriter the combination of a curved type-bearing surface, electromagnets, an armature adapted to be moved in opposite directions by said magnets, mechanism actuated by said armature to move said type-bearing surface, and another electromagnet adapted to act in conjunction with said first-named magnets to effect an additional movement of said type-bearing surface and means to additionally move said mechanism from the position to which it is moved by said first named magnets.

15. In a telegraph typewriter the combination of a curved type-bearing surface, electromagnets, an armature adapted to be moved in opposite directions by said magnets, mechanism actuated by said armature to move said type-bearing surface, another electromagnet adapted to act in conjunction with said first-named magnets to effect an additional movement of said type-bearing surface, and a group of magnets adapted to act in conjunction with the aforesaid magnets to modify the movements of the said mechanism.

16. In a telegraph typewriter the combination of a curved type-bearing surface, a group of electromagnets, an armature adapted to be moved in opposite directions by said magnets, mechanism actuated by said armature to move said type-bearing surface, and another group of electromagnets and an armature therefor adapted to be moved in opposite directions, and means actuated by said last-named armature to modify the movements of said mechanism.

17. In a telegraph typewriter the combination of a curved type-bearing surface, electromagnets, an armature adapted to be moved in opposite directions by said magnets, and mechanism actuated by said armature to move the type-bearing surface comprising an arm, and yielding connections between said armature and arm to permit of a momentary overthrow of the latter.

18. In a telegraph typewriter the combination of a curved type-bearing surface, electromagnets, an armature adapted to be moved in opposite directions by said magnets, and mechanism actuated by said armature to move said type-bearing surface comprising an arm, and yielding connections between said armature and arm to permit a momentary overthrow of the latter, and means to modify the movements of said arm without affecting the operations due to said armature or the mechanism which permits the overthrow.

19. In a telegraph typewriter the combination of a curved type-bearing surface, electromagnets, an armature adapted to be

held in normal position centrally between said magnets and adapted to be moved in opposite directions by said magnets, stops normally in position to limit the extent of movement of said armature in opposite directions, means actuated by said armature to move said type-bearing surface, and means to simultaneously release said stops to permit of a further or additional movement of said armature beyond the corresponding stop.

20. In a telegraph typewriter the combination of a curved type-bearing surface, electromagnets, an armature adapted to be moved in opposite directions by said magnets, an arm and connections between the same and said armature to effect a movement of said type-bearing surface when the armature is moved, and means to effect a movement of said connections different from the aforesaid movement by said armature to impart a further or additional movement to said type bearing surface than that imparted thereto by the first named movement of the armature.

21. In a telegraph typewriter the combination of a type wheel, a pinion mounted on the shaft thereof, a sector engaging said pinion, a pivoted arm on which said sector is carried, electromagnets, and means actuated thereby to move said sector in opposite directions, and a second group of magnets adapted to modify the movements of said arm irrespective of the movements of the armature of said first-named magnets.

22. In a telegraph typewriter the combination of a type wheel, mechanism for rotating the same comprising electromagnets, an armature adapted to be moved in opposite directions by said magnets, an arm connected to and adapted to be moved by said armature, a second group of magnets and an armature therefor adapted to be moved in opposite directions, and means actuated by said last-named armature to effect a longitudinal movement of the connection between said arm and the first-named armature to modify the movements of said arm.

23. In a telegraph typewriter the combination of a type wheel, means for rotating said wheel comprising a group of electromagnets, an armature adapted to be moved in opposite directions by said magnets, an arm and connections between the same and said armature including a slotted plate, a second group of magnets and an armature therefor connected to said plate and adapted to move the same longitudinally in either direction to thereby modify the movements of said arm.

24. In a telegraph typewriter the combination of a type wheel, and mechanism for positioning said wheel for printing comprising a plurality of groups of magnets, means for energizing one or more magnets

70

- of each group by successive impulses, armatures for said magnets and means actuated thereby to effect the ultimate position of said wheel irrespective of the order of 5 movements of said armatures.
25. In a telegraph typewriter the combination of a type wheel, and mechanism for positioning said wheel for printing comprising three groups of magnets, means actuated by the magnets of the first and second groups for differentially rotating said wheel, by the combined action of said magnets, and means actuated by the magnets of the third group to move said wheel 10 in a plane at right-angles to the plane of its movement by the magnets of the first and second groups.
26. In a telegraph typewriter the combination of a type wheel, and mechanism for 20 positioning said wheel for printing comprising electromagnets, an armature mounted between said magnets and adapted to be moved thereby in either direction, means actuated by said armature to rotate the type 25 wheel in either direction, a second series of electromagnets and means actuated thereby to modify the extent of movement of said wheel due to said first-named magnets, and a third series of magnets and means actuated thereby to move said wheel in a direction longitudinally of its axis.
27. In a telegraph typewriter the combination of a type wheel, and mechanism for 30 rotating said wheel comprising two groups of electromagnets, means actuated by the magnets of one group to rotate said wheel in either direction, and means actuated by magnets of the other group to rotate said wheel either in the same or the opposite direction due to the first-named group of magnets.
28. In a telegraph typewriter the combination of a type wheel, and mechanism for 35 rotating said wheel in opposite directions comprising electromagnets, an armature adapted to be moved in opposite directions by said magnets, stops to limit the extent of movement of said armature, and a magnet and means actuated thereby to remove said stops out of the path of said armature to 45 permit a further movement thereof and means to impart additional movement to the type wheel from the point at which the type wheel was arrested by one of said stops.
29. In a telegraph typewriter the combination of a type wheel, and mechanism for 50 positioning said wheel comprising groups of magnets and means actuated thereby to move said wheel a definite amount, stops to limit the extent of movement of said wheel, a magnet included in each group and means actuated hereby to adjust said stops to permit a further movement of said wheel and means to impart additional movement to the

type wheel from the point at which the type wheel was arrested by one of said stops.

65

30. In a telegraph typewriter the combination of a type wheel, and mechanism for rotating said wheel comprising magnets, an armature therefor adapted to be moved in opposite directions, means intermediate said 70 armature and wheel and actuated by said armature to move the wheel a given amount, a second group of magnets adapted to act in conjunction with said first-named magnets to modify the movements of the type 75 wheel due thereto, stops to limit the extent of movement of said wheel, and a magnet included in each group to control the position of said stops.

75

31. An electric circuit controlling system 80 comprising a plurality of groups of working magnets, means for selectively energizing a magnet or magnets of each group, a line relay and contacts therefor, and means for shifting the circuits of the line relay 85 contacts to said groups successively upon the opening of a line relay contact.

80

32. An electric circuit controlling system comprising a plurality of groups of working magnets, an operating circuit and a 90 holding circuit for the magnets of each group, a switching relay in the holding circuit, a line relay and contacts therefor, and means actuated by said switching relay to shift the circuits of the line relay contacts 95 to said group successively upon the opening of a line relay contact.

90

33. An electric circuit controlling system comprising a plurality of groups of working magnets, circuits for said magnets, means 100 for selectively energizing a magnet or magnets of each group, a line relay and contacts therefor, a switching relay in the circuit of each group of magnets, and means for energizing said switching relays upon the opening 105 of a line relay contact to shift the circuits of the line relay contacts to said groups successively.

105

34. An electric circuit controlling system comprising a plurality of groups of working magnets, a line relay and contacts therefor, an operating circuit and a holding circuit for each group of magnets, means comprising relays for switching the circuits of the line relay contacts to said groups successively, and means for maintaining said relays energized and the holding circuits closed until all of the operating circuits have been energized.

115

In testimony whereof I have hereunto 120 signed my name in the presence of two subscribing witnesses,

ALLEN D. CARDWELL.
